United States Patent Office

Des. 190,899
Patented July 18, 1961

190,899

BEVERAGE DISPENSER

Eugene E. Goodrich, Park Ridge, and Joseph R. Mango,
Midlothian, Ill., assignors to The Bastian-Blessing
Company, Chicago, Ill., a corporation of Illinois

Filed Aug. 18, 1960, Ser. No. 61,813

Term of patent 14 years

(Cl. D2—3)

FIG. 1

FIG. 2

FIG. 3

FIG. 4

FIG. 5

FIG. 1 is a view in front elevation of the beverage dispenser, showing our new design;

FIG. 2 is a view in side elevation of our design, the opposite side being a mirror image thereof;

FIG. 3 is a view in rear elevation thereof;

FIG. 4 is a bottom plan view of FIG. 2 of our new design; and

FIG. 5 is a front perspective view thereof on an enlarged scale.

We claim:

The ornamental design for a beverage dispenser, as shown and described.
